UNITED STATES PATENT OFFICE.

EDWARD HAROLD BOUDWIN, OF PHILADELPHIA, PENNSYLVANIA, ASSIGNOR OF ONE-SIXTH TO DANIEL W. HARNER, ONE-SIXTH TO ROBERT L. WORSING, ONE-SIXTH TO CARL M. GAGE, AND ONE-SIXTH TO JAMES A. PFOUTS, ALL OF PHILADELPHIA, PENNSYLVANIA, AND ONE-SIXTH TO AMBROSE E. YOHN, OF HUNTINGDON, PENNSYLVANIA.

TELEPHONE SYSTEM FOR RAILWAY-TRAINS.

1,148,141.

Specification of Letters Patent. Patented July 27, 1915.

Application filed November 27, 1911. Serial No. 662,722.

To all whom it may concern:

Be it known that I, EDWARD HAROLD BOUDWIN, a citizen of the United States, residing at Philadelphia, in the county of 5 Philadelphia and State of Pennsylvania, have invented certain new and useful Improvements in Telephone Systems for Railway-Trains, of which the following is a specification.

10 My said invention consists in various improvements in the details of construction and arrangement of parts of a telephone system for use on railway trains whereby articulate speech may be transmitted between the locomotive driver and any other member of the 15 train crew on any car, or other part of the train, all as will be hereinafter more fully described and claimed.

Referring to the accompanying drawings 20 which are made a part hereof and on which similar reference characters indicate similar parts: Figure 1 is a diagrammatic view of a portion of a railway train illustrating the application of my said invention thereto, Fig. 2, a similar view on an enlarged scale 25 of a fragment the ends of two railway cars illustrating the means of establishing electrical connection from one to the other and forming a part of my said system, Fig. 3, a 30 side elevation of an angle cock of a form such as is in common use as a part of the air brake equipment on railway trains but containing contact plates forming part of my said invention, Fig. 4, a cross section on 35 the dotted line 4—4 in Fig. 3, Fig. 5, a detail view of a pipe tap for use in connection with said angle cock, Fig. 6, a cross section through the same on the dotted line 6—6 in Fig. 5, Fig. 7, a detail view partly 40 in section and partly in elevation showing the connection between the two parts of the hose coupling, Fig. 8, a detail view of a 45 hose nipple for use in the end of the section of hose between the cars, Fig. 9, a cross section on the dotted line 9—9 in Fig. 8, Fig. 10, a cross section through the hose, as on 50 the dotted line 10—10 in Fig. 2, and Figs. 11 and 12, detail views illustrating the electrical contacts between the parts of the hose coupling on an enlarged scale.

In said drawings the portions marked A represent the angle cock; B, B¹ the two parts

of the hose coupling; C, the hose nipple, and D, the pipe tap.

The angle cock A, as shown in Fig. 3, is of 55 the same general form as the angle cocks in common use, except that it is recessed on opposite sides of its interior and contact plates 10, 11, 12 and 13 are mounted in said recesses, being embedded in insulating material 14, and connected with binding posts 15, 16, 17 and 18, respectively, to which circuit wires may be connected as will be presently described. In lieu of this form of angle cock the tap D shown in Figs. 5 and 6 may be substituted to establish the electrical connection with the common angle cock without any change in its structure, as will be readily understood by an inspection of said figures, said tap being adapted 70 to be connected with the angle cock by a screw threaded connection.

The hose coupling consisting of the two parts B and B¹ is also of a common type and requires no special description. 75

Terminal contact plates 19 and 20 are mounted in the bearing face of lip b of part B and corresponding contact plates 21 and 22 are mounted in the co-acting lip b¹ of part B¹. Like contact plates are mounted 80 in the lip b² of part B and corresponding contact plates are mounted in the co-acting lip b³ of part B¹. One of said contact plates, 23, of part B, and one, 25, of part B¹ are shown in Fig. 7, but the other pair are not 85 shown, the arrangement being a duplication of that shown in Figs. 11 and 12. Said several contact plates are each insulated from the respective parts of the couplings, as shown, and when the parts are coupled, as 90 shown in Fig. 2, the co-acting contact plates of the respective parts bear against each other and establish an electrical connection.

The hose nipples C are mounted in the opposite ends of the hose sections C¹ and are 95 formed with screw threaded sections for connection with the angle cocks, as is usual. Longitudinal contact strips 27, 28, 29 and 30 are mounted in longitudinal grooves in said screw threaded section in position for 100 contact with the contact plates 10, 11, 12 and 13 of the angle cock. The rear ends of said plates 27, 28, 29 and 30 are bent upwardly at right angles and rest in recesses in the

flange of said nipple and are perforated to receive the ends of the circuit wires. Said contact plates are insulated from said nipples, as shown.

5 Each hose section C¹ is formed with several, preferably five, wires embedded in the material, as rubber, of which it is composed. Said wires project beyond the ends of the hose sections and four of them at one end 10 are connected with the contact plates 27, 28, 29 and 30, while the fifth extends into a perforation c in the flange of the nipple and is electrically connected thereto. The four wires which are connected, respectively, at 15 one end to the contact plates 27, 28, 29 and 30 also project from the opposite end of the hose section and pass through perforations and connect, respectively, with the contact plates 19 and 20 on one side of one part of 20 the hose coupling B¹ and with the corresponding contact plates on the other side.

A cable 40 containing four wires extends from end to end of each car, the ends of the four wires being respectively connected to 25 the binding posts 15, 16, 17 and 18 on adjacent end of the angle cock on the respective ends of the "train line", or air pipe, on said car. Said train line or pipe is insulated at all points from the hangers and 30 brake mechanism. It will thus be seen that five metallic conductors are established throughout the length of the train, which, with the connection to the track, or ground, makes six lines or three complete circuits.

35 In the use of this system a telephone, as 50, of any approved type is installed in the cab of a locomotive and another is installed in a convenient part of each car throughout the train. The telephones are connected in 40 one or the other of the several circuits above described and a switch 51, of any suitable type, is provided whereby either wire or circuit may be used interchangeably. By thus providing a number of wires or conductors, 45 as six in the present instance, a considerable number of circuits are available and can be utilized interchangeably and the interruption of the use of the apparatus by one or more circuits becoming broken or interrupted is thus guarded against. Such an 50 apparatus being installed in all the cars and locomotives of a railway system, the making up of any train, or the switching of cars from one train to another, does not in any 55 manner interfere with the use of the system, for, as soon as the air line is connected throughout the train, which must be done as soon as a car is attached to a train, a circuit is complete and the telephone system placed 60 in operative condition.

While I have shown the telephone circuit coupling as embodied in the air brake coupling, it will be understood, of course, that it may be embodied in any other mechanical coupling which must of necessity be con-

nected in order to establish an operative train.

The invention is as applicable to freight as well as to passenger trains and by its use the conductor in the cab car at the rear of the train may readily and instantly communicate with the locomotive driver at the other end of the train whenever necessity or convenience requires. By this means the time required by the present system for communication is not only saved, but the purpose of the communication is accurately secured and misunderstandings, with the resulting danger and delays, are avoided.

Having thus fully described my said invention, what I claim as new and desire to secure by Letters Patent, is:

1. A telephone signal system for railway trains, comprising a combined electrical and mechanical coupler or joint forming a part of the necessary air-brake line connection between the several component parts of the train, conductors constituting several circuits through which articulate speech may be had between various parts of the train connected with terminals in said couplers, telephone apparatus located in the several component parts of the train and connected in said circuits to provide means for said articulate speech, and switches for connecting said telephones in said several circuits interchangeably, whereby connection may be made between any part of the train and any other part of the train, substantially as set forth.

2. In a telephone system for railway trains the combination of a telephone apparatus, electric circuits connecting a telephone apparatus in one part of the train with a telephone apparatus in the other several parts of the train, said circuits being carried from one component part of the train to another through the air brake line and comprising contact plates connected in said circuits and mounted in the coupling members of the air brake line and contact plates mounted in the angle-cocks, and wires connecting the sets of contact plates, substantially as set forth.

3. In a telephone system for railway trains the combination of a telephone apparatus located in the several component parts of the train, an electric circuit connecting said telephones comprising contact plates with which the wire terminals are connected embedded in insulating material and mounted in recesses in the air brake line coupling members and in the angle-cocks of the air brake line, said contact plates and the coupling members being arranged to contact automatically with the coupling of said air brake line, substantially as set forth.

4. A telephone system for railway trains comprising telephones located in several component parts of the train, several elec-

trical circuits connecting from end to end of the train, contact plates to which the circuits are connected, carried by and brought into contact through mechanical coupling devices operable with the air brake line coupler, said telephones being connected interchangeably in said several circuits, substantially as set forth.

In witness whereof, I have hereunto set my hand and seal at Washington, D. C., this 16th day of November, A. D. nineteen hundred and eleven.

EDWARD HAROLD BOUDWIN. [L. s.]
